UNITED STATES PATENT OFFICE

AUGUST RUESCH, OF UNION CITY, NEW JERSEY

DESIGN FOR IRISH LACE

Application filed March 5, 1932. Serial No. 43,086. Term of patent 3½ years.

To all whom it may concern:

Be it known that I, AUGUST RUESCH, a citizen of the United States, residing at Union City, in the county of Hudson and State of New Jersey, have invented a new, original, and ornamental Design for Irish Lace, of which the following is a specification, reference being had to the accompanying drawings, forming part thereof.

The fragmentary portion of the lace illustrated in the drawings is a complete repeatable unit of the design.

I claim:

The ornamental design for Irish lace as shown and described.

AUGUST RUESCH.
